STAYBOLT

Ralph W. Friday, Pittsburgh, Pa.

Application October 4, 1932, Serial No. 636,152
Renewed July 6, 1937

14 Claims. (Cl. 85—1.5)

This invention relates to staybolts and particularly to flexible staybolts of the tell-tale type, which may be tested to determine their condition.

One object of this invention is to provide a stay-bolt of improved construction to permit its condition to be easily and quickly tested.

Another object of this invention is to provide an improved method of testing boiler staybolts to determine their condition.

Another object of my invention is to provide a new and improved staybolt structure assembly.

If staybolts are broken it renders the boiler unsafe for use. It is, therefore, essential to have some means of determining the condition of the staybolt. At present, flexible staybolts are tested by one of two methods, either by removing the boiler jacket, lagging, and caps, and then applying the hammer test, or, in case hollow flexible bolts are used, the electric contact method is used to determine whether or not the tell-tale hole is open all the way into the head. In case the hole in a bolt is not open all the way into the head, the hole is cleaned out and thereafter the boiler is put under hydro-static pressure to detect broken or badly fractured bolts by leakage of water or steam through the tell-tale hole of a fractured bolt into the firebox. If sediment in a bolt is so hard that it covers the fracture so that the water cannot enter the tell-tale hole then the present method of testing will not indicate the real condition of the bolt.

In my invention the necessity of employing either of these methods of test is eliminated and the condition of the flexible staybolts is quickly and easily determined without any previous preparation of the boiler for the purpose of making the test. In testing a bolt according to my invention, I include the bolt in an electrical circuit which is broken or which has its resistance materially increased by a faulty condition of the bolt.

A bolt embodying my invention is provided with a longitudinal hole or bore extending throughout its length or extending at least from the firebox end of the bolt into the head of the bolt at its other end. In this hole I insert an insulated rod or core preferably of metal or alloy. The insulation on the outer surface of this rod prevents contact of the rod with the staybolt except within the head of the bolt where the rod is electrically bonded or connected to the bolt. The rod is therefore insulated electrically from the bolt shank or body throughout the entire length of the bolt body in which breakage may occur. In the bolt assembly structure, the head of the bolt is, in turn, insulated from the boiler sheet by being

provided either with an insulating layer disposed between the head proper and a bearing ring encircling the head, or by an insulating medium disposed between the head of the bolt and its seat in the sleeve or boiler plate. I have also practiced my invention by employing a sleeve which is provided with an annular bearing member which forms a seat for supporting the head of the bolt, this annular bearing member being insulated electrically from the sleeve.

With an assembly such as I have described, an electric current may pass from the tip of the rod or core at the fire sheet end of the bolt, along the core to the head of the bolt, thence back toward the fire sheet by means of the bolt body itself, so that a testing circuit may be completed through the bolt by contacting the tip of the bolt core and the sheet or the firebox end of the bolt by the terminals of a suitable testing circuit, including, for example, a low voltage battery connected in series with an electric light or other current-responsive or voltage-responsive indicator.

If the bolt is sound, and such contact as above described is made, the light bulb or indicator will become energized, but, if the bolt is broken the light bulb will not be illuminated or the indicator energized to any degree. I do not confine myself to this particular method of indicating the flow of electrical current, to indicate the condition of the bolt, since any resistance-measuring scheme may be used, as desired.

In this way it may be ascertained whether or not the bolt is broken. This constitutes a simple and improved method for determining the condition of a flexible staybolt.

The novelty and basic difference of my invention from the present method is in the fact that the present method of electrically testing the hollow or tell-tale type of flexible staybolt only indicates whether the tell-tale hole is open throughout the bolt into the headed end, but does not test the condition of the bolt, whereas my invention actually tests the bolt itself and indicates whether the bolt is broken.

Various modifications of the bolt and bolt structure assembly are shown in the accompanying drawings, in which

Figure 1 is a front elevational view of a bolt embodying the principles of this invention;

Figure 2 is a longitudinal sectional view of the bolt in Figure 1;

Figure 3 is a view, partially in section and partially in elevation, of a bolt assembly structure of one form embodying the principles of this invention, and illustrating how the bolt may be tested

by a suitable contact device at the end of the individual bolt;

Figure 4 is a longitudinal sectional view of the bolt in Figure 2 in position in an assembly;

5 Figures 5 and 6 are longitudinal sectional views of modified bolt assembly; and

Figure 7 is a sectional view of the outer-sheet end of a further modification of a bolt structure.

As shown in Figures 1 and 2, a staybolt 10, constructed in accordance with the principles of my invention, embodies a cylindrical shank or body 11 and an enlarged head 12 integral therewith. The bolt body 11 has a central longitudinal passage or orifice 13 extending the length of the body 15 of the bolt to a point 14 in the enlarged head.

In order to provide a freely available terminal to connect an external electric circuit to the end of the bolt body adjacent the head, I provide a rod or core 15 in the bolt passage 13 and 20 join the inner end of the rod to the bolt in any suitable manner, such as by welding, to provide a good electrical contact with the head end of the bolt body. The rod is electrically insulated from the bolt body along its length by a layer of 25 any suitable insulation 16, such as a non-conducting refractory or asbestos material.

In order to otherwise insulate the bolt from the structure in which it may be located, so that there may be no leakage of testing current 30 through the structure and the adjoining bolts, the head of the bolt is formed of two co-operating and closely fitting sections 17 and 18 insulated from each other to introduce a layer of insulation between the bolt head and body and 35 the sheet at which the head will be disposed.

The upper section 17 of the head contains a recess 19 such as slot or square hole for driving the bolt and is integral with the body 11. The lower section 18 of the head constitutes a 40 cylinder shaped to fit over the body or shank of the bolt along a part 21 of the longitudinal periphery of the bolt, and also shaped to rest against a shoulder 22 on the under side of the head section 17. A layer of insulating material 45 23 is disposed between the two co-operating sections 17 and 18 to prevent current leakage between them.

The lower section 18 serves as a seat or bearing ring for the bolt head 17 to permit the bolt 50 to re-adjust itself as may become necessary during operation.

The condition of the bolt body may thus be tested easily by reason of the two ends or terminals of the bolt body available for connection to an electric circuit, through the center rod 15 and the tip or threaded end 24 of the bolt body. For such testing purposes a simple circuit may be employed, as shown in Figure 3, containing a source of current 26, a meter, light bulb or other 55 indicating device 27, and a two-point terminal plug 28.

In Figure 3 is shown a bolt structure assembly comprising a modified form of bolt 31 having the same center passage and core rod but having a 60 solid head 32. The head 32 is seated on an insulating ring or bushing 33 which rests against a sleeve 34 that is to be secured to a sheet or plate 30 that is to be held in position by the bolts. The insulating ring 33 may be of metal 65 with a film or layer of insulating asbestos or the like 37 between its outer surface and the surface of the sleeve 34. A cap screw 35 serves to close the sleeve 34, which is welded to the sheet or plate 30 by a joint 36.

75 The lower surface of the bolt head is curved

where it engages the inner surface of the bearing ring 33 to permit the bolt head to adjust itself under the varying temperature conditions encountered in the boiler structure held together by the bolts. The insulating layer 37 between the bearing ring 33 and the sleeve 34 prevents electrical contact between the bearing ring and the sleeve, and thereby prevents current leakage from the head end of the bolt when the testing circuit is applied. The path of the testing current is thus confined to the center rod and the shank or body of the bolt. The resistance of a normal bolt will lie between certain values as predetermined by measurements of known normal bolts. A variation of resistance of a tested 15 bolt from the range of average values will indicate a faulty bolt.

The central core rod should be joined to the bolt head at a point well into the head and beyond the juncture of the head and the body, in 20 order to include the entire length of the bolt body in the testing circuit.

Figure 4 shows the bolt of Figure 1 in position between two sheets or plates 40 and 41. The head is seated in a threaded sleeve 42 having a 25 spherical socket 43 for receiving the head of the bolt. The lower part of the sleeve threads into plate 40 and the upper part of the sleeve supports a cap screw 44 for closing the socket chamber of the sleeve 42. In order to prevent 30 engagement between the upper section 17 of the head and the surface of the socket of sleeve 42, due to adjustments of the head in the socket, the insulating layer 23 is preferably disposed to cover the adjacent surface of the upper section 35 17 or the upper section 17 may be cut back slightly for a short distance back from the circle of contact between the two sections.

The lower end or tip 46 of the bolt body is peened over on sheet 41 to secure the bolt in 40 place. The tip of the bolt and the end of the core rod 15 may now be utilized as terminals to connect the bolt body into an electric test circuit, as shown in Figure 3 to be tested. By means of this construction, a test of each bolt may be 45 easily and quickly made without necessitating cleaning out the central passage as required by present practice, since contact with the head end is available through the core rod 15.

A plug 48 may be inserted in the end of the 50 bolt to cover the end of the rod. When the bolt is to be tested, the plug is removed.

Two general types of flexible staybolts are in use at present. One type consists of a bolt with an integral enlarged head of the same material 55 as the body of the bolt. The other type of bolt consists of a bolt body having a separate head, said head having its inner surface threaded and screwed onto the bolt body and being secured to the end of the bolt by welding, peening or other 60 suitable method. A staybolt is subjected to such transverse and vibratory stresses that a ductile and elastic metal is required to withstand these stresses as well as the ordinary tensile stress to which the bolt is subjected when the boiler is in 65 service.

The bearing surface of the bolt head is subjected to a great deal of friction as it moves in its seat, and, unless the metal of bolt head can withstand this wearing satisfactorily, it will sometimes freeze or adhere to the metal forming the seat in which the bolt head rests, thereby locking and eventually breaking the bolt.

If a separate head is screwed onto the body of the bolt as hereinbefore described, the cutting 75

of the threads in the bolt into the separate head weaken the latter to such an extent that breakage of the separate head often occurs.

The bolts and the assembly structures embodying the principles of my invention have the two characteristics required, namely, ductility and a satisfactory wearing surface, by using a bearing ring as the seating section of the head of the bolt and making it of a material that will satisfactorily withstand friction; have sufficient strength to prevent breakage during service and be adapted to fit under the head of the bolt in such a manner as to lose none of its strength and give a smooth wearing surface to fit into the seat in which it rests, and by using a material for the body of the bolt that gives ductility and strength. The seat for the bearing ring may be in the boiler sheet with an opening for the bolt, as will be described hereinafter with reference to Figures 5 and 6, or the seat may be in a sleeve secured to the boiler sheet, as shown in Figures 3 and 4.

In Figure 3, the bearing ring 33 is not considered as a part of the bolt head, but rather as an independent seating element. In Figure 4, however, the lower section 18 of the head is considered as a part of the head although it is not an integral part. In that modification, the outer surface of the lower section is part of a spherical surface. For appearance, the outer surface of the top section 17 is a part of a spherical surface. In Figure 3 the under surface of the bolt head, where it engages the bearing ring 33, is preferably spherical to provide maximum ease of flexing of the bolt.

In Figures 5 and 6 are illustrated further modifications embodying various features of my invention.

In Figure 5 the bolt 50 is seated with its lower head-section 51 directly in a recess in the outer sheet or plate 40. The lower head section 51 is insulated from the main head section and serves as the bearing ring which adjusts itself in the boiler sheet or plate 40. A cap 54 is provided to cover the head of the bolt and has its inner surface 55 insulated. The cap is secured to the boiler sheet 40.

In Figure 6, the other bolt modification is shown, with which a bearing ring 60 is provided, seated in and insulated from the boiler sheet 40 by a suitable insulating medium 61. A cap 62 covers the head of the bolt and is secured to the boiler sheet 40. The inner surface of cap, 63, is insulated. I reserve the right to use a cap in assemblies Figures 5 and 6 without an insulated inner surface.

In Figure 7 is shown a modification similar to that in Figure 3 except that the sleeve 70 and the bearing ring 71 have outer surfaces of cone-shape to provide a tight seating fit. The bearing ring is insulated from the sleeve by an insulating medium 72.

This principle of using a bearing ring of satisfactory and proper bearing metal may be utilized for solid bolts, as in Figure 7, as well as for hollow bolts of the tell-tale type, since the advantage of a proper bearing surface may be utilized independently of the testing advantage.

My invention is not limited therefore to any of the specific structural details, since they may be variously modified without departing from the spirit and scope of the invention as set forth in the appended claims.

I claim as my invention:

75 1. A staybolt comprising a head, a hollow bolt

body and an electrical conducting element disposed in, and extending the length of, the hollow body and electrically insulated from the body along its length but electrically connected to the body at the head end of the hollow passage, said conducting element being of sufficient self-sustaining character and strength to be unaffected by fracture of the bolt body or by the resultant leakage, and serving to permit an electrical test of the bolt structure under all operating conditions. 10

2. A staybolt comprising a head and a hollow body integral therewith, and means electrically connected to the head end of the hollow body and integral therewith but insulated from the body throughout its length, said means being of sufficient self-sustaining character and stability to be unaffected by leakage resulting from fracture of the bolt body and serving to permit an electrical connection to be readily made to the head end 20 of the bolt under all operating conditions of the bolt.

3. A staybolt comprising a head, a hollow bolt body, and an electrical conductor connected permanently to the head end of the bolt body and 25 extending to the tip of the bolt body and insulated from the bolt body, said conductor being of sufficient self-sustaining character and stability to be unaffected by leakage resulting from fracture of the bolt body, and serving to be available 30 for electrical testing of the bolt under all operating conditions while it is in position.

4. A staybolt structure comprising a bolt having an enlarged head, a bearing ring on the bolt and adapted to fit against the under surface of the head, the outer surface of the bearing ring constituting a section of a sphere, to permit the bolt and the ring to move freely to enable the bolt head to adjust its position, as necessary, in an assembled structure, and a permanent electrical insulating medium between the head and the bearing ring. 40

5. A staybolt comprising a bolt having an enlarged head, a seat for the head having its outer surface constituting a section of a sphere and an electrical insulating medium between the seat and the head, to permit the bolt and the seat to move freely to enable the bolt head to adjust its position, as necessary, in an assembled structure. 45

6. A staybolt for use between two sheets of a boiler structure, comprising a hollow bolt having an enlarged head, a conducting core extending the full length of the hollow bolt and electrically joined thereto at the head end but insulated along its length, whereby both ends of the bolt 55 body may be connected in an electrical circuit for testing the conductivity and condition of the bolt, and a bearing ring on the bolt and fitting against the under side of the head but electrically insulated therefrom by a suitable insulating medium whereby the head of the bolt may be insulated from the sheet when the bolt is secured in position.

7. A staybolt structure comprising a staybolt with a tell-tale hole extending from one end of the bolt into but not through the head of the bolt, and means for electrically insulating the head of the bolt from the boiler sheet, under normal operating conditions, to permit electrical testing of the bolt as a unit without current leakage to the boiler sheet from the head end of the bolt. 70

8. A staybolt for use between two sheets of boiler structure, comprising a hollow bolt having an enlarged head, a conducting core extending 75

the full length of the hollow bolt and electrical-
ly joined thereto at its head end but insulated
along its length, whereby both ends of the bolt
body may be connected in an electrical circuit
5 for testing the conductivity and condition of the
bolt, and a bearing ring on the bolt and fitting
against the under side of the head but electrical-
ly insulated therefrom by a permanent insulat-
ing medium whereby the head of the bolt may
10 be insulated from the sheet when the bolt is se-
cured in position, and a removable plug in the
tip or fire sheet end of the bolt.

9. A staybolt structure comprising a staybolt
with a head and hollow bolt body integral there-
15 with and electrical conducting core joined to the
bolt body at its head end but insulated from the
bolt body along its length, a sleeve secured to
the boiler sheet, a permanent electrical insulating
medium between the head of the bolt and the
20 sleeve, and a closure over the head of the bolt.

10. In a staybolt structure, the combination
with a boiler sheet provided with an opening for
the head of a staybolt, of a staybolt comprising
a head, a hollow bolt body integral therewith and
25 a permanent electrical conducting core joined to
the bolt body at its head end but insulated from
the bolt body along its length, an insulating me-
dium between the head of the bolt and the
boiler sheet, and a closure over the bolt head
30 and secured to the sheet.

11. A staybolt structure comprising a staybolt
with an enlarged head, a hollow bolt body in-
35 tegral therewith and an electrical conducting
core joined to the bolt body at its head end but

insulated from the bolt body along its length, a
bearing ring on the bolt and adapted to fit under
the head, one surface of the bearing ring con-
stituting a section of a sphere, a permanent elec-
trical insulating medium between the bearing 5
ring and the boiler sheet, a boiler sheet provided
with an opening for the head of the bolt and a
closure over the bolt head and secured to the
boiler sheet, the closure having the inner sur-
face electrically insulated. 10

12. A staybolt structure comprising a staybolt
with an enlarged head, a hollow bolt body in-
tegral therewith and a conducting core joined
15 to the bolt body at its head end but electrically
insulated from the bolt body along its length, a
bearing ring on the bolt and adapted to fit
under the head, one surface of the bearing ring
constituting a section of a sphere, an electrical 20
insulating medium between the bearing ring and
the sleeve, a sleeve secured to the boiler sheet
and a closure over the head of the bolt.

13. The method of assembling a staybolt struc-
ture for a boiler, which consists in installing the
staybolts with their head ends permanently insu-
lated from the boiler sheet, whereby any bolt 25
body may be electrically tested without diversion
of testing current from the bolt being tested.

14. The method of testing staybolts in a stay-
bolt structure, which consists in insulating the
head of the bolt from an associated metal sheet, 30
and applying electrical testing potential to both
ends of the body of a staybolt being tested.

RALPH W. FRIDAY.
